REFRIGERATING APPARATUS

Harry M. Williams and Albert J. Timmer, Dayton,
Ohio, assignors to General Motors Corporation,
Dayton, Ohio, a corporation of Delaware

Application December 31, 1934, Serial No. 759,812

4 Claims. (Cl. 230—206)

This invention relates to refrigerating systems and particularly to the means employed in such systems for causing circulation of refrigerant therein.

5 An object of the present invention is to prevent absorption of refrigerant in a closed volatile refrigerating system by oil employed to lubricate moving parts of the refrigerant circulating element or compressor of the system through which the refrigerant is circulated.

Another object of the invention is to provide a refrigerating system with a refrigerant circulating element or compressor which has a substantially dry crankcase compartment as distinguished from conventional refrigerating systems wherein a body of lubricant is ordinarily contained in the crankcase of the compressor thereof.

In carrying out the foregoing objects it is a still further object of the invention to force a lubricant, such, for example, as oil, through or between the bearing surfaces of operating parts of a compressor of a refrigerating system, to drain the lubricant circulated to the compressor parts from the compressor, and to isolate the lubricant removed from the compressor from refrigerant in the refrigerating system.

Further objects and advantages of the present invention will be apparent from the following description, reference being had to the accompanying drawing, wherein a preferred form of the present invention is clearly shown.

In the drawing:

Fig. 1 discloses a refrigerating system shown diagrammatically and having my invention embodied in the refrigerant circulating element thereof which element is shown on an enlarged scale partly in section and partly in elevation; and

40 Fig. 2 is a sectional view through the oil pump employed in the present invention and is taken on the line 2—2 of Fig. 1.

Referring in detail to the drawing there is shown for the purpose of illustrating the invention a compressor-condenser-expander type of refrigerating system employing an expansion valve for admitting refrigerant to the evaporator of the system and a thermostat responsive to temperatures of the evaporator for actuating a switch for intermittently or cyclically starting a and stopping operations of the system. However, the invention is equally applicable to a so-called flooded type refrigerating system in which a float valve controls the entrance to the evaporator and in which operation of the system is controlled by a switch responsive to pressures in the sys-

tem. My invention may be of more importance when applied to the latter type of a refrigerating system due to the relatively large amount of refrigerant in such system and which refrigerant is ordinarily circulated in absorbing contact with the lubricant contained therein.

5 The system disclosed in the drawing comprises a refrigerant circulating element, pump or compressor 10 operated by an electric motor 11. The compressor or pump 10 forces refrigerant such as difluorodichloro methane (CCl₂F₂) or any other suitable refrigerant through a suitable check valve, which is ordinarily contained in the top portion or head 12 of the compressor, and thence through conduit or pipe 13 into a condenser 14. The compressed refrigerant is condensed and liquefied in condenser 14 and collects in the receiver 16. From the receiver 16 the liquefied refrigerant passes by conduit 17 through an expansion valve 18 and into the cooling coils 19 or evaporator 19 of a refrigerating element where it performs its refrigerating effect in the well-known manner. From the cooling coil 19 the vaporized refrigerant passes by means of the pipe 21 back to the refrigerant circulating element, 15 pump or compressor 10. The thermostatic device is represented by the numeral 22 and is disposed so as to be responsive to the temperature of the cooling coil 19 or may be responsive to the temperature of the space being refrigerated by this 20 coil. This device is used to actuate, as by means of a diaphragm, bellows or the like 23, a circuit-making and breaking switch 24. This switch is shown in its motor non-operating position by the 25 full lines and contacts 25 and 26 and in its operating position by the dotted line.

30 After the system is put in operation and the compressor 10 has been idle for a short period of time, pressure within the evaporator 19, pipe 21, and the compressor crankcase 28 is relatively 35 high. During this idle period the temperature of a fluid in bulb 22 rises and increases its own vapor pressure and this pressure acting inside the flexible diaphragm or bellows 23 will expand same and thus force the switch 24 and its contacts 25 and 26 into circuit-making position to 40 cause operation of the motor 11 employed for driving the refrigerant circulating element, pump or compressor 10. After the compressor has operated for a short period, say for a few minutes, the temperature and the environment of bulb 22 45 is reduced, and the fluid pressure therein is reduced sufficiently to permit the diaphragm or bellows 23 to be contracted, thus actuating the switch contacts 25 and 26 into open position for 50 breaking the electric circuit to the motor 11. 55

Operations of the system continue as described as long as such system is connected with the source of power. The compressor, or pump 10 may be of any suitable form and may include an eccentric 31 within the crankcase 28 which eccentric is secured to the rotating shaft 32 and has a connecting rod 33 actuated thereby. Movement of the connecting rod 33 reciprocates a piston 34 secured to the upper end thereof. This piston 34 has located therein any suitable or conventional check valve (not shown) which opens upon the down stroke of the piston to permit the entrance of refrigerant gas into the cylinder 36 above the piston but seats or remains closed during the up or compression stroke thereof.

The crankcase 28 of the compressor, or pump 10 is on the "low side" of the system. While the compressor is operating, the refrigerant pressure therein is relatively low, but during the idle period this pressure gradually rises because of the rise of temperature of the liquid refrigerant in the low side of the system. During this idle period, therefore, the refrigerant absorbing power of lubricant ordinarily contained as a body thereof in the crankcase of conventional compressors increases and a quantity of refrigerant is absorbed, depending, of course, on the natural affinity between the two fluids, the temperature of the lubricant and the pressures of the fluids.

The volume of the lubricant in conventional compressor crankcases (which is a mixture of oil and refrigerant with a major portion of oil) therefore tends to increase due to this absorption of refrigerant during the idle periods of the system. This is particularly true where the refrigerant and lubricant are miscible in all proportions, but the same problem exists, in varying degrees, even when they are only partially miscible. A body of oil as contained in the crankcase of conventional compressors is thereby readily diluted thus decreasing the lubricating properties thereof.

In a conventional apparatus not provided with my invention, the lubricant level would tend to rise to a detrimentally high level during the idle period of the system. This rise in the level would occur because of the absorption of the refrigerant by the lubricant as described above. With such a detrimentally high oil level a violent boiling or foaming would occur when the compressor starts due to the release of gaseous refrigerant from the lubricant by the quick reduction in pressure. Under such conditions large amounts of liquid are likely to pass through the valve, not shown, but located in the piston 34 into the compression chamber 36 above the piston with undesirable results such as causing stalling of the motor 11 and burning or blowing of fuses in the power circuit. A great amount of oil is also circulated by the pump or compressor with refrigerant to other elements of the refrigerating system and this is likely to cause the compressor to operate without being properly lubricated.

According to this invention, however, the problems encountered in the use of conventional compressors are eliminated. To this end there is provided an apparatus wherein the pump or compressor crankcase 28 is maintained in a substantially dry condition or in other words, is devoid of a body of lubricant therein while at the same time providing positive and efficient lubrication of moving parts of the pump or compressor 10. Referring again to the drawings it will be noted that the compressor, or pump 10 disclosed therein has its operating shaft 32, which is rotated by

operation of the motor 11, extending to a point adjacent a counter-bored opening or chamber 40 provided on one side of the compressor crankcase 28. A unitary pump, preferably although not necessarily, of the vane type, the construction and operation of which pump is well-known to those skilled in the art, is adapted to be located within the chamber 40. The pump includes a rotor 41 having two vane members 42 and 43 located in a slot provided therefor in the rotor and which vanes are forced outwardly away from one another by a spring 44. A ring member 45 is stationarily clamped, by screws 46, between an end plate 47 and another end plate 48 which said another end plate is stationarily clamped to the wall of chamber 40 by a plurality of bolts or screws 49. The ring 45 is mounted concentrically with respect to chamber 40 and compressor shaft 32 and is provided with an eccentric opening which serves as a cylinder in which the rotor 41 rotates. In order to cause rotation of rotor 41 within the eccentric cylinder provided by ring 45 the rotor is provided with shaft portions 51 and 52 formed integrally with and extending outwardly from each side of the rotor. The shaft portion 51 of rotor 41 is journaled in an opening provided therefor in the end or sealing plate 48. The other shaft portion 52 of rotor 41 has its end squared as at 53 so as to be received in a similarly shaped groove or slot 54 provided in the end of the compressor shaft 32. (See Fig. 2.) The connection of shaft portion 52 with the compressor shaft 32 obviously causes operation of the pump just described when the compressor 10 is operated by motor 11. During rotation of the rotor 41 a suction is created on one side of the annular edge of the rotor between the vanes 42 and 43 and at the same time a pressure is created on the other side of rotor 41 between the vanes 42 and 43 as is well-known to those familiar with pumps of the type disclosed. Therefore I provide suitable outlet openings 55 in the uppermost portion of ring 45 on the pressure side of the pump and also a similar inlet opening 56 (see Fig. 1) on the suction side of the pump. The outlet openings 55 communicate, by means of the notch or groove 57 provided in ring 45, with an outlet port or conduit connection 58 and with the chamber 40, by means of the notch or groove 59 provided in the end plate 47 for purposes to be more fully described hereinafter. The inlet opening 56 which, as before stated, may be similar to the outlet openings 55 is, of course, blocked off or prevented by end plate 47 from communicating with the pressure chamber 40 but this inlet opening 56 is in open communication with an inlet port or conduit connection 61. A specific type of pump having been briefly described, it will be understood, however, that any suitable or conventional pump may be employed to carry out the objects of the present invention.

A closed fluid circuit is connected to the pump above described and is adapted to contain, in one portion thereof, a quantity of oil to be circulated to or through the bearing surfaces of moving parts of the compressor 10 for lubricating such parts. A conduit 65 is adapted to have its one end connected, by any suitable connecting means, with the outlet port or connection 58 of the pump and the other end of conduit 65 is adapted to be connected to a connection 66 in the housing 67 of a valve device generally designated by the reference character 68. The valve device 68 has a pipe connection 69 with the lowermost portion of the interior of the crankcase 28 of com- 71

pressor 10 and is also connected, by the flange coupling 71 and copuler 72, with a tank 13. A conduit 74 is adapted to have its one end 75 connected, by any suitable connecting means, with the bottom of tank 13 and the other end 76 of conduit 74 is adapted to be connected with the inlet connection 61 of the oil pump secured to and operated by the compressor 10. The valve device 68 included in the closed fluid pressure circuit just described includes a plunger 81 having a valve 82 attached thereto or formed on the lower end thereof and which valve is adapted to open or close the passage 83, leading from conduit or pipe 69 through housing 67 to the tank 13, in a manner to be hereinafter described. The plunger 81 has a shoulder 84 formed thereon and is hollowed out as at 85. An opening or port 86 provided in plunger 81 permits communication between the chamber 81, which receives the enlarged shoulder portion 84 of the plunger, and the passage 83 in housing 67. The communication between chamber 81 and passage 83 provided by the opening 86 is for the purpose of equalizing the pressure on each side of the plunger 81 and for permitting its free movement when pressure is applied to chamber 81 beneath the shouldered portion 84 thereof. A spring 88 normally tends to force plunger 81 downwardly so that valve 82 closes the conduit or passage 83 extending from the compressor crankcase to the tank 13 when the pump attached to the compressor is idle.

The chamber 40 of the oil pump is in open communication with the outlet connection 58 thereof and is also in open communication with a passage 91 provided in the center of the operating shaft 32 of the compressor 10. The passage 91 in the shaft 32 communicates with any desired number of grooves, passages, etc., provided in other operating parts of the compressor which are attached or connected to the shaft 32 and are to be lubricated by oil circulated by the oil pump. For example, the passage 91 may communicate with a hole extending to the surface of the shaft 32 and communicating with a feeding groove or the like provided in the eccentric 31 which leads to the groove 92 in the connecting rod 33. The groove 92 communicates with an opening or hole 93, in the connecting rod 33, which extends to an opening 94 provided in the wrist-pin 95 for permitting the connection or bearing surfaces of the wrist-pin with the rod 33 and piston 34 to be lubricated. The method of grooving and providing the oil feeding holes in shaft 32 and the other operating parts of the compressor 10 is well-known to those skilled in the art of providing forced lubrication to operating parts of engines, compressors, etc.

Substantially all of the oil employed in the apparatus disclosed for lubricating the moving parts of the compressor 10 is contained in the tank 13 of the closed oil circuit comprising the compressor 10, conduits 65, valve device 68, conduit 14 and the oil pump. When the refrigerating system is put into operation to cause intermittent or cyclical operations of compressor 10, for withdrawing evaporated or gasified refrigerant from the evaporator 19 and for circulating the compressed refrigerant to the condenser 14, the oil pump connected with the compressor or pump shaft is also operated. Operation of the oil pump sucks or draws oil through the inlet opening 56 and conduit 74 from the reservoir thereof in tank 13 and forces this oil through the outlet openings 55, notch or slot 57, and through slot or groove 59 to chamber 40. Since the outlet

connection 58 is also in open communication, by way of the slot 57, with the openings 55 oil is also forced, by pressure created by the pump, to the conduit 65. The oil under pressure is circulated from chamber 40 into the central hole 91 provided in the compressor or pump shaft 32 from where it is caused to flow to the bearing surfaces of the shaft 32, thence through groove 92 to the bearing surface between the connecting rod 33 and eccentric 31. The oil is also forced, under the pressure created by the pump, from the groove 92, through opening 93 in rod 33, to the hole 94 in the piston pin 95 thereby lubricating the bearing surface of operating parts of the compressor. As before stated oil under pressure is circulated to conduit 65 simultaneously with the circulation thereof to the bearing surfaces of the various parts of compressor 10. The pressure created by the oil pump or the oil flowing to conduit 65 is forced through the conduit connection 66, in the valve device 68, into the bottom of chamber 87 below the enlarged portion of plunger 81 provided by the shoulder 84 formed thereon. The pressure of the oil pump or the oil beneath the plunger 81 causes the plunger to move or to be actuated upwardly to thereby lift valve 82 and open the passage 83 leading from the compressor crankcase to the tank 13. The pressure created by the oil pump during operation of the compressor 10 maintains the plunger 81 in its uppermost position and thereby maintains valve 82 in its open position as long as the compressor is operating. Therefore oil flowing from the bearing surfaces of moving parts of compressor 10 drips to the inclined bottom wall of the crankcase 28 and flows therefrom, through the pipe 69 and passage 83, to the interior of tank 13. The compressor crankcase 28 is thereby maintained in a substantially dry condition or in other words, is free of a body of oil and thus the oil does not accumulate therein. When the compressor stops the pressure throughout the closed oil circulating system equalizes and the plunger 81 in the valve device 68 is moved by spring 88 to its lowermost position to close valve 82 to cut off communication between the compressor crankcase 28 and the oil reservoir in tank 13. The oil employed for lubricating the moving parts of compressor 10 and which flows from these parts to the trap 13 during operation of the compressor is thereby isolated or maintained out of contact with the refrigerant employed in the refrigerating system. In case some oil is carried through the compressor 10 during the running period thereof it eventually finds its way back to the compressor crankcase 28 and to the oil circulating circuit after passing through the condenser and evaporator with the refrigerant in the refrigerating system.

Thus it is apparent that there is provided an improved refrigerating system which will not be rendered inoperative by the absorption of refrigerant of the system by a body of lubricant in the compressor. There is provided a refrigerating apparatus in which the lubricant and refrigerant employed therein are miscible or partially miscible and in which the miscibility or mixing thereof is prevented so as to eliminate the difficulties of hard starting, etc., of the compressor which occurs in conventional refrigerant pumps or compressors. The invention therefore prevents the refrigerant of the refrigerating system from diluting the lubricating oil and consequently proper and efficient lubrication of the operating parts of the compressor is insured. The invention provides a compressor having a sub-

stantially dry crankcase and oil will not be circulated from the compressor to other elements of the refrigerating system, thus problems, inherently present in conventional refrigerating systems, of returning oil from certain elements of the refrigerating system to the compressor crankcase are eliminated.

While the form of embodiment of the invention as herein disclosed, constitutes a preferred form, it is to be understood that other forms might be adopted, all coming within the scope of the claims which follow.

What is claimed is as follows:

1. In combination with a compressor employed to circulate a refrigerant through a refrigerating system in which the refrigerant is miscible with a lubricant contained in the system, means for circulating the lubricant to operating parts of the compressor, said means being rendered effective by operation of the compressor for circulating the lubricant to operating parts thereof, means for conducting the circulated lubricant away from said compressor, means connected with said conducting means for receiving lubricant conveyed from said compressor, said lubricant receiving means also having a connection with said lubricant circulating means for supplying it with lubricant to be circulated, means rendered effective upon stopping the operation of said compressor for closing said conducting means to isolate the lubricant removed from said compressor from refrigerant in the refrigerating system, and said last named means also being rendered effective automatically in response to operation of said compressor for opening said conducting means.
2. In combination with a pump employed to circulate a refrigerant through a refrigerating system in which the refrigerant is miscible with a lubricant contained in the system, a second pump for circulating the lubricant to operating parts of said first named pump, said second named pump being rendered effective simultaneously with operation of said first named pump, means for conducting the circulated lubricant away from said first named pump, means connected with said conducting means for receiving lubricant conveyed from said first named pump, said lubricant receiving means also having a connection with said lubricant pump for supplying it with lubricant to be circulated, means rendered effective upon stopping the operation of one of said pumps for closing said conducting means to isolate the lubricant removed from said first named pump from refrigerant in the refrigerating system, and said last named means also being

rendered effective automatically in response to operation of one of said pumps for opening said conducting means.

3. In combination with a compressor employed to circulate a refrigerant through a refrigerating system in which the refrigerant is miscible with a lubricant contained in the system, said compressor having a substantially dry crankcase through which refrigerant flows during circulation thereof through the system, a pump connected to and operated by said compressor for circulating the lubricant to operating parts of the compressor, conduit means for conducting lubricant from operating parts of the compressor and for preventing accumulation of lubricant in the compressor crankcase, a reservoir connected with said conduit means for receiving lubricant conveyed from said compressor for supplying it with lubricant to be circulated, said lubricant reservoir having a connection with said pump, a valve for controlling the flow of lubricant through said conduit means, said valve being actuated automatically to open said conduit means by pressure created by operation of said pump, and said valve being actuated automatically upon stopping the operation of said pump to close said conduit means for isolating lubricant removed from said compressor from refrigerant in the refrigerating system.

4. In combination with a compressor employed to circulate a refrigerant through a refrigerating system in which the refrigerant is miscible with a lubricant contained in the system, a pump for circulating the lubricant to operating parts of the compressor, said pump being operated simultaneously with operation of said compressor, conduit means for conducting lubricant away from said compressor, a reservoir connected with said conduit means for receiving lubricant conveyed from said compressor, said lubricant reservoir having a connection with said pump for supplying it with lubricant to be circulated, a spring pressed valve for controlling the flow of lubricant through said conduit means, means communicating with said pump and with said valve whereby pressure created by said pump overcomes the force exerted by said valve spring, said valve being actuated automatically to open said conduit means upon operation of said pump, and said valve being actuated automatically upon stopping the operation of said pump to close said conduit means for isolating lubricant removed from said compressor from refrigerant in the refrigerating system.
